UNITED STATES PATENT OFFICE.

FRANK R. WILLIAMS, OF OTTUMWA, IOWA.

DRILL.

1,210,747.

Specification of Letters Patent. Patented Jan. 2, 1917.

Application filed August 24, 1914. Serial No. 858,404.

To all whom it may concern:

Be it known that I, FRANK R. WILLIAMS, a citizen of the United States, and resident of Ottumwa, in the county of Wapello, State of Iowa, have invented a certain new and useful Drill, of which the following is a specification.

The object of my invention is to provide a drill of the pneumatic type, capable of imparting intermittent, rotary motion to the drill shank.

More particularly, it is my object to provide a drill of the pneumatic type, in which is mounted a piston operatively connected with the drill shank, which drill is provided with a clutch device and is so constructed and arranged that the steady feeding of compressed air or steam imparts an intermittent, rotary motion to the drill shank, as above mentioned.

My invention consists in certain details, in the construction, combination and arrangement of the various parts of the device, whereby the objects contemplated are attained, as hereinafter more fully set forth, pointed out in my claim and illustrated in the accompanying drawings, in which:

Figure 1 shows a vertical, central, sectional view through a drill, embodying my invention. Fig. 2 shows a perspective view of the lower end of the piston. Fig. 3 shows a detail, sectional view of a modified form of my device, and Fig. 4 shows a detail, sectional view, taken on the line 4—4 of Fig. 3.

In the accompanying drawings, I have used the reference numeral 10 to indicate generally a hollow cylinder or casing into the upper end of which is screwed a body 11, having an upwardly extending, annular wall 12 which surrounds a cup shaped opening in the upper end of the body 11. The upper end of the wall 12 is formed with an outwardly extending, circumferential, annular flange 13. Resting above the flange 13 is a plate 14, formed on the lower surface of which is a downwardly extending, annular flange 15, received within the cup formed by the walls 12 and the body 11. The inner surface of the flange 15 is beveled from the top downwardly and outwardly, as shown in Fig. 1, to form one part of a clutch, and said flange will hereinafter be called a clutch member.

Slidably mounted in the interior of the

body or cylinder 10 is a piston 16. Between its ends, the piston 16 is provided with an annular groove 17 of considerable width, as shown. At the lower end of the piston 16 is a downwardly extending portion 18, cylindrical in cross section and smaller in diameter than the body of the piston 16. Formed on the lower end of the cylindrical portion 18 is a downwardly extending, angular portion 19. Screwed into the lower end of the body or casing 10 is a bushing 20. Formed on the outside of the lower end of the bushing 20 is a downwardly extending sleeve 21 which on its interior, near its upper end, is provided with an annular shoulder 22. Received within the sleeve 21 is a sleeve 23 having an angular opening extending through it, the proper size and shape to receive the extension 19 to permit the sliding movement of said extension with relation to said sleeve 23 but to cause the sleeve and extension to rotate together when the piston is rotated. The sleeve 23 is designed to receive the upper end of the drill point 24. The upper end of the sleeve 23 is enlarged to provide a shoulder 25 to fit against the shoulder 22, for holding the sleeve 23 against removal from the sleeve 21.

Mounted on the member 14 and secured to said member and to the flange 13 by means of the bolt 26 is a suitable handle 27. Received within the cup formed by the walls 12 and body 11 inside the clutch member 15 is a clutch member 28 having the form of a frustum of a cone, and having a downwardly extending stem 29 slidably extended through the body 11. On the lower end of the stem 29 is a portion having the thread 30. In the upper end of the piston 16 is an opening or hole 31. Screwed into the upper end of the piston 16 is a plug 32 having a screw threaded hole through it provided with threads which coact with the threads 30. The threads just described are of wide pitch. The hole in the plug 32 registers with the hole 31 and the hole 31 is deep enough to allow considerable longitudinal movement of the stem 29 with relation to the piston 16 when the members in the piston and the stem 29 are rotated with relation to each other. The opening in the center of the casing or body 10 is of sufficient length to permit considerable longitudinal movement of the piston 16 within said cas-

ing 10. In the wall of the casing 10, near the upper end of the opening therein, is a by-pass 33 communicating with the interior of said casing 10 at points spaced from each other, as shown in Fig. 1. Near the lower end of the opening in said casing 10 is another by-pass 34, communicating with said opening at points spaced from each other, as shown in said Fig. 1.

10 The wall of the casing 10 is provided with openings 35 and 36, spaced from each other longitudinally in said wall. At a point between said discharge openings is an intake passage or opening 37 with which communicates a feed pipe 38, for furnishing compressed air. The clutch member 28 and the stem 29 are provided with the longitudinal opening 39, extending from the upper surface of the clutch member downwardly a sufficient distance. A lateral opening 40 communicates with the interior of the casing 10 and with the passage or opening 39.

15 The parts hereinbefore described are of such construction that the practical operation of my improved drill is as follows: Assuming the parts to be in the position shown in Fig. 1, air is supplied through the supply pipe 38 and passes into the groove 17, thence through the by-pass 34 to the space 20 around the portion 18 of the piston 16 below the shoulder 42. The upward pressure of the air against the shoulder 42 forces the piston upwardly. Upward pressure is imparted on the clutch member 28, which is thereby locked in position. It will be understood of course that the clutch member is normally held locked by the spring 41 surrounding the stem 29 between the body 11 and the lower surface of the 25 clutch member 28. It will therefore appear that during the upward movement of the piston 16, the effect of the screw members 30 and 32 will be to rotate the piston 16. The portion 19 of the piston will slide upwardly but at the same time will rotate the sleeve 23, which in turn will rotate the drill point 24.

30 When the piston moves upwardly and the groove 17 clears the upper end of the by-pass 34, the expansion of the air in the space around the member 18 will continue to force the piston toward the upper limit of its movement although the passage of the air or other fluid through the pipe 38 will be stopped during part of the upward movement of the piston.

35 When the piston has moved upwardly to the point where the upper end of the groove 17 registers with the lower end of the by-pass 33, air from the pipe 38 will pass upwardly through said by-pass to the space above the piston. At about the same time the shoulder 42 moves to position above the lower 40 part of the discharge passage 36 and per-

mits the air in the lower part of the casing 10 to be discharged. The piston then tends to move downwardly. Air passes through the passages 40 and 39 to the space above the clutch member 28 forcing the clutch member 28 downwardly and releasing it from engaging with the clutch member 15. The pressure of the air starts the piston downwardly and its downward movement is continued by the expansion of the air by 45 gravity.

50 On account of the fact that the clutch members are not in engagement, the piston 16 does not rotate during its downward movement. It will thus be seen that the constant pressure of the air from the pipe 38 causes an intermittent, rotary movement of the drill point 24, and causes an alternating, reciprocating movement of the piston 16. During one stroke of the piston 16 it is rotated and during the other stroke its movement is longitudinal only.

55 In Fig. 3 I have shown a modified form of the clutch member. Formed on the plate 14 in the modified form of the invention is a corrugated lower face 50. Formed on the stem 29 is a plate or clutch member 51, having its upper face corrugated. The central adjacent portions of the clutch members 50 and 51 are cut away to form openings 52 and 53. The opening 53 communicates with the passage 39. The other parts are substantially of the same construction as shown in Fig. 1.

60 Fig. 3 shows a vertical, central, sectional view, with the exception that the members 50 and 51 are shown partially in elevation to better illustrate their construction. The operation of the parts is the same as that already described.

65 My improved drill has a number of advantages, many of which may be seen from the foregoing description. By the use of compressed air or other suitable fluid, I am able to impart to the drill an intermittent rotary motion by means of the continuous air pressure furnished through the supply pipe 38. The parts are of comparatively simple construction and are so assembled that they may be readily and easily taken apart for repairs or replacing worn parts.

70 It will be understood that some changes may be made in the details of the construction of my improved drill without departing from its essential features and it is my intent to cover any such changes which may be included within the scope of my claim.

75 I claim as my invention:

80 In a device of the class described, a hollow casing, a piston having a longitudinal opening in the upper end and adapted to reciprocate therein, means for reciprocating said piston, a clutch member fixed within the upper end of the casing, a second clutch member adapted to coact with the first and 85

of such shape as to form an air chamber between said clutch members, a rifle bar fixed to and extending downwardly from the last described clutch member into the opening 5 in the piston, said rifle bar having a passage therein connecting the air chamber and the upper end of the casing, a nut fixed within the opening in the piston and adapted to

coact with the rifle on the bar, and means for yieldingly holding said clutch members in engagement.

Des Moines, Iowa, August 11, 1914.
FRANK R. WILLIAMS.
